US00D775180S

(12) United States Design Patent (10) Patent No.: US D775,180 S
Caldwell (45) Date of Patent: * Dec. 27, 2016

(54) DISPLAY SCREEN OR PORTION THEREOF WITH A GRAPHICAL USER INTERFACE

(71) Applicant: MX Technologies, Inc., Lehi, UT (US)

(72) Inventor: John Ryan Caldwell, Lehi, UT (US)

(73) Assignee: MX TECHNOLOGIES, INC., Lehi, UT (US)

() Term: 15 Years

(21) Appl. No.: 29/553,415

(22) Filed: Feb. 1, 2016

Related U.S. Application Data

(63) Continuation of application No. 29/542,985, filed on Oct. 20, 2015, now Pat. No. Des. 750,660, which is a continuation of application No. 13/507,601, filed on Jul. 12, 2012.
